UNITED STATES PATENT OFFICE.

ARTHUR R. KRAUSE, OF WOODHAVEN, NEW YORK, ASSIGNOR TO THE LION ELECTRIC MANUFACTURING CO., INC., A CORPORATION OF NEW YORK.

DESIGN FOR A LIGHTING-FIXTURE PLATE OR SIMILAR ARTICLE.

Application filed July 16, 1926. Serial No. 18,378. Term of patent 7 years.

To all whom it may concern:

Be it known that I, ARTHUR R. KRAUSE, a citizen of the United States, and a resident of Woodhaven, county of Queens, and State of New York, have invented a new, original, and ornamental Design for a Lighting Fixture Plate or Similar Article, of which the following is a specification, reference being had to the drawing, forming a part thereof.

In these drawings:

Figure 1 is a side elevational view of the

lighting fixture plate or similar article; and Figure 2 is an inverted plan view of the lighting fixture plate or similar article, the part shown in full line outline being ornamented in the same manner as the part more fully illustrated.

I claim:

The ornamental design for a lighting fixture plate or similar article substantially as shown and described.

ARTHUR R. KRAUSE.
